[57] CLAIM

The ornamental design for an electronic calculator, as
shown and described.

DESCRIPTION

FIG. 1 is a top plan view of the electronic calculator
showing my new design;

FIG. 2 is a bottom plan view thereof;

FIG. 3 is a front elevational view thereof;

FIG. 4 is a rear elevational view thereof; and

FIG. 5 is a right side elevational view thereof, the left
side elevational view being the same.

FIG. 1

FIG. 2

FIG. 3

FIG. 4

FIG. 5
